UNITED STATES PATENT OFFICE.

GEORGE CRAWFORD ELLIOTT, OF BROOKLYN, NEW YORK, ASSIGNOR, BY DIRECT AND MESNE ASSIGNMENTS, TO GEORGE CRAWFORD ELLIOTT, WILLIAM H. SISSON, AND HUDSON T. MORTON, TRUSTEES, DESIGNATED AS THE ELLIOTT TYPEWRITER COMPANY, OF BROOKLYN, NEW YORK.

BOOK TYPE-WRITER.

1,255,397.

Specification of Letters Patent.

Patented Feb. 5, 1918.

Substitute for application Serial No. 639,599, filed July 20, 1911. This application filed March 8, 1917. Serial No. 153,530.

To all whom it may concern:

Be it known that I, GEORGE CRAWFORD ELLIOTT, a citizen of the United States, residing in Brooklyn, county of Kings, and State of New York, have invented certain new and useful Improvements in Book Type-Writers, of which the following is a full, clear, and exact specification.

This invention relates to improvements in book typewriting machines in which in efforts to make them "visible" writing, the type bars and their type are arranged in a semi-circle, with the key board directly over and above the type bars, with the result that for the necessary use of 40 type bars the arc of a circle is so great that there is unavoidably a side action of the key levers, making the touch of the machine too heavy for successful practical operation, which is not only aggravated by a high key board difficult of operation because of its elevation, but presenting an obstruction compelling the operator to an awkward neck and body stretching for inspecting the writing, which he must quite frequently do, for the purposes of practical and perfect work, and as a consequence of which there is substantially no demand for machines of such construction, even desirable as it is to have, to this limited degree, a visible book typewriting machine.

My invention, more specifically relates to improvements in book typewriting machines generally and commercially known as the "Elliott & Hatch book typewriter" with a view to making it a "visible" writing machine, for the reason that it has a very low key board, which may be further lowered by my invention, and a basket of shallow depth formed by a continuous circle of type bars, each of which supports a plurality of type, and which, as a whole, has successfully stood the test of practical use for many years, because of its durability in construction, and effectiveness in operation and capability for turning out good work.

In the "Elliott & Hatch book typewriter," as well as in all other book typewriting machines, in which the type levers are arranged in a continuous circle, the type levers at the rear half of their circle or basket of the machine are actuated by key levers extending from the keys across the circle, and necess-

sarily so concealing the type impressions, with the result that the operator is required to bodily swing the quite heavy type carriage upwardly above its operative position until the writing is brought to view beneath the carriage, an operation requiring considerable strength of hand and arm, and the necessary and frequent repetition of which is not only tiresome but a substantial loss of time in the operation of the machine.

The arrangement of the type bars in continuous circular form in book typewriting machines has been demonstrated by long and extensive usage to be more desirable than any other form of arrangement, in that it enables the machine, as a whole, to be of minimum compactness, maximum durability in wear, convenience and stability of adjustment, ease of action and lightness of touch, which latter two features are essential to rapid and perfect work, which ease of action and lightness of touch are substantially promoted by affording the operator a natural position both of body, arms and hands, and thereby giving him the greatest possible command of the keys and ease of movement in their manipulation, both of which are essential to accurate work when prolonged or rapid or both, and also to a direct and positive movement of the key levers and other parts of the machine.

The desirability and necessity of a visible writing book typewriting machine has been known and sought to be secured for many years, and ever since book typewriting machines have been a practical and commercial success, and many efforts have been made and large sums of money expended by others and myself to avoid the necessity of elevating the type carriage for inspecting the writing in machines in which the type bars form a complete arch, and in low basket form and with a low key board.

Prior to my invention, however, these efforts have been unsuccessful, because of the impossibility of securing sufficient and uniform ease of action and lightness of touch when the connections between the key board and the type levers are, as must be, outside of the basket before it is possible to utilize the opening through the basket for the purpose of visibility of the writing as it pro-

gresses, one of the essentials of which is that the key board must not project in a plane above the basket, and that for the greatest possible convenience of inspection of the writing the basket shall be in depth as shallow as is consistent with the length of type bars necessary for their practical operation.

The prime object of my invention, broadly stated, is, therefore, a book typewriting machine having the lowest possible key board, shallow depth of basket and lightness of action, and in which the writing is accessible, plainly and conveniently visible to the operator as it progresses in the absence of any necessity of lifting the type carriage from its operative position.

A further object of my invention is to retain in a visible writing book typewriting machine the old and well known circular arrangement of type bars, the location and connection of the key levers with the type bars forming the front half of their complete circle, and to operate from keys in lower planes than those first above mentioned the key bars of the rear half of the basket by means unobstructing the opening through the basket, whereby the writing of the machine as it progresses may be clearly visible to the operator at any time without lifting the type carriage.

Most specifically stated, the object of my invention is to make it possible and practical to locate and arrange all of the key levers outside of and laterally beyond the basket formed by a circular arrangement of the type bars of a book typewriting machine, and to so connect said levers with the type bars from the rear half of said circle that a perfect ease of action of the key levers, type bars and lightness of touch of the keys may be maintained through the medium of shaft connections at a point between the keys and the type bars.

A further object of my invention is to provide means by which the Elliott & Hatch machine construction may be converted into a visible writing book typewriting machine with its key board lowered, as a whole, below its previously low position and yet retain its circular arrangement of type bars, and the construction or arrangement of the type bars of the front half of their circle therein, or the key levers for actuating said bars.

With these ends in view, my invention finds embodiment in certain features of novelty in the construction, combination and arrangement of parts by which the said objects and certain other objects are hereinafter attained, all as fully described with reference to the accompanying drawings, and more particularly pointed out in the claims.

In said drawings:—

Figure 1 illustrates a top plan view of a visible book typewriting machine in which

my invention finds embodiment, with some of the key and key levers, and also the ring for actuating the type heads omitted for the purpose of clearness of other parts.

Fig. 2 is a detail sectional plan view with parts broken away to more clearly show the shaft connections between the key levers and the typebars at the rear of the circle in which they are arranged; and,

Fig. 3 is a detail side elevation for clearly showing the novel arrangement and connections between the type bars and key levers, the means by which the shiftable type heads are actuated and maintained in their adjustment, and the means for shifting the ribbon when uncovering the writing for inspection.

Similar characters of reference indicate the same parts in the several figures of the drawings.

As the means for supporting and the mechanism for propelling the type carriage forms no part of my present invention, I have shown (see Fig. 1) only the side bars 4-4 of the open frame, the end bars 5 and 6 of the slideable frame mounted thereon, the shaft 7 upon which the type carriage is swung, the rack bar 8 embedded in said shaft for engagement with the pinion 9 of the propelling mechanism 10, and of the construction and arrangement heretofore commonly used for many years in the Elliott & Hatch book typewriter, and in which the carriage is sustained by means of pulleys 11, 11 on studs 12 projected from the legs 13 from an arch plate resting from the bed plate 14 of the type carriage, which also supports grooved wheels 15, 15 and 16, 16 embracing the opposite sides of the shaft 7 in the usual manner and for the purposes of steadyng the type carriage in its travel along its supporting shaft 7, the arch plate and bed plate being, as usually, in the form of an angular casting secured to the usual bottom ring 17 of the basket-like structure 18, the sides of which are closed by the type bars in circular arrangement.

To the ring 17, toward the front side thereof, are secured the outwardly projecting brackets 19, supporting, (see Figs. 1 and 3) by means of screws 20, an upper plate 21 and a lower plate 22 connected together at their ends, as indicated at 23, and forming, as a whole, an open oval-like plate, to the outer end of which are secured lifting levers 24, 24 respectively provided with finger pieces 25 and 26 as a convenient means for swinging it on its supporting shaft 7 when occasion may require.

In a plane above the base ring 17 and supported by one or more suitable rods 27 is a ring 28, within which and the ring 17 are arranged, in the rear half of their circle, type bars 29, and in the front half of their circle type bars 30, to the usual total num-

ber of forty, secured toward their lower ends by pivots 31 to hangers 32 and the latter are secured by means of screws 33 passing into the ring 17 from its underside, segmental plates 34 connecting several such screws and operating as washers therefor.

All of the type bars are of the same form and all those in the front half of the circle are connected with and by their key bars in the same manner and by the same devices heretofore used, namely, (see Fig. 3) by a rod 35 pivoted to the bent lower arm 36 of the typebar, and by a clip 37 pivoted directly to a key lever 38, the fulcrum of which is in a clip 39 depending from the plate 21 at the front side of the machine.

In this connection, it should be noted that the upper two banks of keys 40 and 41 of this machine are at the same elevation and in the same position as the lower two banks of the four rows of keys in the Elliott & Hatch book typewriting machine.

In order to have the opening through the basket free and clear of obstruction, as may be for visibility of the writing as it occurs, some other means must obviously be provided as a means of connecting the type bars in the rear half of their circle with their respective key levers, and in such a manner that the operation of the type bars and key levers shall be respectively easy of action and touch, and at the same time the key levers and their connections be out of the way of the key levers for the type bars of the front half of the machine.

To these ends there are respectively supported upon the ring 17 (see Figs. 2 and 3) at both front corners thereof, plates 42, each provided in its inner and diagonal edge with angular recesses 43, from which and preferably bent are perforated lugs 44, and on the carriage of the bed plate in a plane above and at opposite corners of the rear side of the machine triangular-like plates 45, in the edges of which are right angle notches 46 and projecting perforated lugs 47.

The lugs 44 are opposed by perforated plates 48, the perforations of which register with those in the lugs, and together with those of the lugs provide bearings for rock shafts 49, differing in length as the lugs are stopped inwardly toward the front side of the machine, while, on the other hand, the shafts shorten from the rear toward the front side of the machine between the opposing lugs 47, as shown in Fig. 1, and as indicated by the long rock shaft 58 and the short rock shaft 51 in Fig. 2, forward of which latter, however, is a shorter rock shaft 52 and a still shorter shaft 53 in a bearing 54 formed by bending the metal upon itself at the apex of its triangular plate bearing.

It should here be observed, however, that there are two lugs 55 at each end of the triangular base line of the plate 45, provided

with perforations 56, 57 in differing horizontal planes, so that long rock shafts 50 and 58, at this point, may be arranged one above the other in order to get such shafts within the boundary permitted by the space 70 present in machines of the construction of the Elliott & Hatch typewriter, and as may be by having the end of one shaft project beyond the other adjacent their connection with the type bars, as indicated by shafts 75 50 and 58 at the upper left hand corner of Fig. 1.

For actuating the key bars in the rear half of their circular arrangement there is projected, for example, from the shaft 58 a crank arm 59, pivoted at its free end to a rod 60, the lower end of which rod is secured to the crank arm 61 of the type bar, the outer end of the shaft 58 being also provided with a crank arm 62 to which is pivoted a rod 63, provided with a turn-buckle 64 for adjusting purposes, the rod in turn being pivoted to a lug 65 toward the outer end of the shaft 49, the opposite end of which shaft, see Fig. 3, is provided with a crank arm 66, pivoted at one end to the crank arm 63 and by a pivot 69 to the horizontal stem 70 of a key lever, upturned at its outer end and seating a key 71, which key lever toward its inner end is provided with a downwardly projecting arm 72 and an inwardly bent projecting arm 73 fulcrumed on a shaft 74, common as a fulcrum to all of the key levers for actuating the type bars in the rear half of their circle.

In this connection it should also be observed that all of the key levers for the type bars, in the rear half of the basket, are of the form and connected with their respective rock shafts in the manner above described, the lengths of the shafts according to the location of the type bars connected therewith, as do also the lengths of the key levers depending from which bank of keys they are to be operated, that is to say, whether, (see Fig. 1) from the bank of keys 75 or 76, it being proper to observe in this connection that in the Elliott & Hatch book typewriting machine on the market there are exclusive of tabulating keys forty keys and forty type levers, which levers in the aggregate carry eighty characters, *i. e.*, upper and lower case letters fifty-two, nine numerals and nineteen punctuations and signs, whereas in the present drawings there are shown and indicated forty-three keys for letters, numerals and signs and eight keys for tabulating purposes, and which my present invention not only provides for, but for having the key board substantially lower than in any other book typewriting machine, visible writing or otherwise, and with the shift keys and space bar 77 at the base of the plane of such a low bank of keys.

With this understanding of the construc- 130

tion, arrangement and operation of the longest shafts with the rearmost type bars of the basket, it is so obvious that other than in decreasing length of shaft connections as 5 the type bars approach, their outermost position in the basket is and must be precisely the same, save that the shafts are gradually decreased in length.

In every instance, however, it will be seen 10 that the force for actuating the shafts and imparted by them to the type bars, is at substantially a right angle to the length of said shafts, with the result that the force is transmitted from the keys to the type bars in the 15 best possible direction for its utilization, and also for promoting ease of action of the several mechanical parts, and lightness of touch as applied to the keys, while at the same time there is no obstruction in the 20 opening through the basket to the writing of the type striking the pages of a book as they do in every instance axially of the circle formed by the keys.

For shifting the ribbon away from the 25 writing for inspecting the same, I may employ a ribbon shifter 78 grasping the ribbon for permitting it to freely pass therethrough and actuating this ribbon shifter by a rod 79, provided with an upwardly bent portion 30 80 having a sliding bearing on a bar 81 and actuated by a duplex crank arm 82, fulcrumed at 83 in a stud 84, operated by the spacing bar mechanism of the machine as commonly constructed, consisting of bent 35 side bars 85 and 86 fulcrumed at the rear of the machine and engaged to each and the several key levers thereof.

So far as the broad idea of my invention is concerned, any other construction of ribbon shifter, adapted for the purposes above 40 described, may be used, and this is also equally true of the ribbon spools 87 and 88 for the ribbon 89 and the actuating devices 90 and 91 therefor, and in short I propose 45 to use in the construction of the machine of my present invention substantially the same feed, ribbon and spacing bar mechanism as has been used for many years in the Elliott & Hatch machine upon the market, and for 50 the purposes of the visibility of the writing of which without lifting the type carriage my present invention is especially designed and adapted.

In other words, the only substantial 55 changes required to convert the old and well known Elliott & Hatch book typewriter into a successful and practical visible book typewriting machine are accomplished by lowering its upper two banks of key levers, 60 below the remaining key levers, substituting therefor the bent levers before described for operating the type bars in the rear half of the basket and connecting them with the shafts in stepped plates mounted respectively upon the lower and upper base portion 65

at the front and back of the machine with the stepped shafts therein connected, as before described, with the type bars.

The construction and arrangement of parts by which the old non-visible Elliott & Hatch book typewriter is made a visible writing machine is so simple and cheap that it may be adapted thereto with success at a cost substantially less than ten per cent. of that of the original machine. 75

Having described my invention, what I claim and desire to secure by Letters Patent is:—

1. A book typewriting machine carriage comprising in combination type bars forming a complete circle of open basket-like arrangement, key levers, and rock shafts extending at a right angle to and connecting said levers, type bars at and for the rear half of the basket, and means for operatively connecting the type bars with said shafts and key levers, substantially as described. 80

2. A book typewriting machine carriage comprising in combination type bars arranged to form a complete circle of open basket-like arrangement, straight line key levers for actuating said type bars, rock shafts of differing lengths located above the bottom of the basket, operatively connected with said key levers and extending at a right angle to the length of the key levers, substantially as described. 90

3. A book typewriting machine carriage comprising in combination type bars in circular open basket-like arrangement, rock shafts in a plane just above the upper ends of the type bars adjacent the rear end of the carriage, crank arm connections between said shafts and the type bars, a corresponding series of shafts in a plane below the upper ends of said type bars, rod connections between the outer ends of the opposing upper and lower shafts, key levers connected with the inner ends of the lower shafts, and a single shaft constituting a fulcrum common to all of said key levers, substantially as described. 100

4. A book typewriting machine carriage comprising in combination type bars forming a complete circle of open basket-like arrangement, key levers for actuating said type bars in the rear half of their circle, the bank of keys for said bars being in a plane below the keys for all other type bars, and connecting rock shafts differing in length but of the same length for corresponding type bars at opposite sides of the basket, substantially as described. 110

5. A book typewriting machine carriage comprising in combination a base ring, bent key levers, a fulcrum therefor below the base ring of the carriage, type bars in circular open basket-like arrangement, the rear half of the typebars of said circle being connected with the key levers at a point sub- 115 120 125 130

stantially above the fulcrum, of the key levers, substantially as described.

6. A book typewriting machine carriage comprising in combination bent key levers fulcrumed below the base of the carriage, rock shafts individually connected with said key levers at a point substantially above the fulcrum, rod connections between said shafts, and a corresponding series of upper shafts, 5 and a crank arm and rod connection of said upper shafts with the type bars, substantially as described.

7. A book typewriting machine carriage

comprising in combination type bars forming a complete circle of open basket-like arrangement, rock shafts, type bars, key levers pivotally connected with each other, the key levers for operating the type bars for the front half of the basket being arranged in a plane above the key levers for operating the type bars for the rear half of the basket.
